UNITED STATES PATENT OFFICE.

HENRY SCOTT CUNNINGTON, OF NEW YORK, N. Y., ASSIGNOR OF ONE-HALF TO JOHN B. TRIPP,
OF PHILADELPHIA, PENNSYLVANIA.

CIGAR-ASH THIMBLE AND PROTECTOR.

No. 886,352.

Specification of Letters Patent.

Patented May 5, 1908.

Application filed January 13, 1908. Serial No. 410,552.

To all whom it may concern:

Be it known that I, HENRY SCOTT CUNNINGTON, a citizen of the United States, residing at New York city, in the county of 5 New York and State of New York, have invented certain new and useful Improvements in a Cigar-Ash Thimble and Protector, of which the following is a specification.

This invention relates to a cigar ash thimble and protector, the object being to provide a thimble which can be readily placed over the lighted end of a cigar so as to protect the same and prevent the ashes from dropping off.

Another object of my invention is to provide a thimble which is so constructed that it will fit any size cigar, and one which will be securely held thereon by frictional contact with the cigar, so that the cigar can be put in 15 the pocket when desired, thereby preventing the throwing away of the same when entering a street car or a building where smoking is prohibited.

Another object of my invention is to provide a thimble with a supporting ring which is formed of non-conducting material such as 20 bone or ivory, whereby the thimble will be supported when the cigar is laid on a table, so as to prevent the finish of the same from being injured by the heat, and to prevent the 25 thimble from rolling.

Another object of my invention is to provide the open end of the thimble with a plurality of spring arms formed by slitting the 30 thimble and bending the portions between the slits outwardly, whereby they will give so as to prevent the thimble from injuring the 35 cigar when being placed thereon.

Another object of my invention is to provide the closed end of the thimble with a plurality of perforations which will allow the cigar to be smoked when the thimble is arranged thereon and yet prevent the ashes from being knocked off and dropping on the 40 clothes of the smoker, and it will be seen that when it is desired to remove the ashes from the cigar, by giving the thimble a sudden tap, the ashes will be knocked off into the thimble, and by removing the thimble the ashes 45 can be emptied into any suitable receptacle.

These objects are obtained by the novel arrangement and construction of parts hereinafter fully described and shown in the accompanying drawings, in which,

Figure 1, is a perspective view of my improved cigar ash thimble and protector, showing it arranged on a cigar. Fig. 2, is a longitudinal section through the same, and, Fig. 3, is a perspective view of the supporting ring detached.

In the drawings A, indicates a thimble which is formed of any suitable material, such as aluminium, tin, silver or gold. The walls of the open end of which are split and the intermediate portions bent outwardly to 55 form a plurality of spring arms, which allows the same to expand to accommodate different size cigars and prevents the cigar from being injured in placing the thimble thereon.

The closed end of the thimble is provided with a plurality of perforations which extend a short distance on the walls of the same, so as to allow free circulation of air, whereby when the thimble is placed on the cigar the cigar can be smoked in the ordinary manner and at the same time the lighted end will be protected so as to prevent the ashes from being knocked off, and it will be seen that when it is desired to enter a building or car where smoking is prohibited the cigar can be placed in the pocket of the smoker without any danger of burning his clothes.

A ring B, is placed on the thimble and held thereon by frictional contact therewith. The ring has its outer circumference formed with eight sides, the intermediate portions between the ends of the sides being concaved, forming points adapted to engage the surface on which the thimble is placed. This ring being especially adapted to protect the hard wood finish of the piece of furniture when a cigar provided with my improved thimble is laid on the same.

The ring is preferably formed of bone or 95 ivory, but can be formed of any suitable non-conducting material, so that the heat from the cigar will not heat the ring, thereby preventing the piece of furniture from being heated when the thimble is laid on the same. It will, of course, be understood that the thimble can be used without the ring, but the ring is found to be of great advantage as it prevents the cigar from rolling.

From the foregoing description it will be seen that I have provided a cigar ash thimble and protector which is exceedingly simple and cheap in construction and one which will

2
be securely held thereon by frictional contact with a cigar whereby it is not liable to be knocked off accidentally.

Having thus described my invention what I claim as new and desire to secure by Letters Patent is:

1. A cigar ash thimble and protector comprising a metal thimble having a plurality of perforations at its closed end, a plurality of splits at its open end forming spring arms, and a supporting ring surrounding said thimble intermediate of the perforations and splits.
2. A cigar ash thimble and protector comprising a thimble having perforated closed end and a plurality of spring arms.
3. A cigar ash thimble and protector comprising a thimble having a perforated closed end, and provided with a plurality of integral spring arms at its open end and a supporting ring arranged around the solid portion of said thimble at its open end, said arms extending outwardly and a ring surrounding said thimble formed of non-conducting material.

4. A cigar ash thimble and protector comprising a thimble having a perforated closed end, the walls of said thimble being provided with spaced slits at its open end, the intermediate portions being bent outwardly to form a plurality of spring arms, and a supporter arranged on said thimble comprising a ring formed of non-conducting material provided with a plurality of concaved sides.

5. A cigar ash thimble and protector comprising a metal thimble having a perforated closed and adjacent wall, the walls of said thimble at its open end being split and bent outwardly to form spring arms, and a ring arranged on said thimble midway between the perforations and splits for supporting said thimble.

In testimony whereof I have signed my name to this specification in the presence of two subscribing witnesses.

HENRY SCOTT CUNNINGTON.
